UNITED STATES PATENT OFFICE.

VIRGINIUS Z. CARACRISTI, OF ALBANY, NEW YORK.

PROCESS OF FEEDING PULVERIZED FUEL.

1,197,909.

Specification of Letters Patent. Patented Sept. 12, 1916.

Original application filed October 4, 1913, Serial No. 793,310. Divided and this application filed June 12, 1914, Serial No. 344,815. Renewed July 29, 1916. Serial No. 112,133.

To all whom it may concern:

Be it known that I, VIRGINIUS Z. CARACRISTI, a citizen of the United States of America, and resident of Albany, in the county of Albany and State of New York, have invented certain new and useful Improvements in Processes of Feeding Pulverized Fuel, of which the following is a specification.

10 This invention relates to processes of feeding pulverized fuel, and the object of the invention is to provide a process of this nature especially adapted for use with reference to steam-boilers and furnaces.

15 Another object of the invention is to provide a short but intense flame and do away with any blowpipe action which is the result of injecting the fuel and air at a high initial velocity.

20 In a preceding application filed by me October 4, 1913, under Serial No. 793,310, I have described and claimed an apparatus suitable for carrying out the process herein described. The present application is a 25 division of the one referred to, no claims being herein made to the apparatus.

The invention will be clearly understood in connection with the description of the apparatus which is shown in the accompanying drawings, it being always understood, however, that the process may be carried 30 out in apparatus of other forms.

In the accompanying drawings, Figure 1 is a vertical longitudinal section through the 35 apparatus, and Fig. 2 is a partial end-elevation of the same.

Similar reference characters indicate corresponding parts in the views.

Referring to the drawings, the fuel-container 10 is provided with a quantity of powdered fuel, and has feeding devices 11 for the pulverized fuel at the lower part thereof. These feeding devices consist of vertically-arranged tubes, one next to the other, and having their ends of different elevations. Each of these tubes is provided with a feeding orifice 14, and within the tubes are arranged helical or screw feeding devices 13. These screws have at their 50 upper ends gear-wheels 25 which mesh with each other, so as to have one gear-wheel rotate the adjacent one. The end gear-wheel meshes with another gear-wheel 15 having a shaft 16, which is driven by suitable driving mechanism. Thus by the driving of the

shaft 16 with its gear-wheel 15, all the gear-wheels 25 are rotated, and thereby the helical feeding members 13 within the tubes 11 are rotated and cause the fuel within the container 10 to be fed by the screws through 50 the tubes 11 and out of the lower orifices 14 thereof. The air intended to be combined with this fuel is forced in at the portion 24, in the direction of the arrows 23, and this current of air strikes the downwardly-flowing 55 finely-divided fuel and forces the same, in the manner shown by the arrows 20, into the current of combined fuel and air, as indicated by the arrows 21. With the combined mixture of air containing oxygen and 60 finely-divided fuel in the manner indicated by the step-shaped feeding device, as shown in Fig. 1, in the bank or plurality of tubes, shown in Fig. 2, a very finely-divided and 65 intimate combination of fuel and oxygen 70 takes place, which is fed in this combined state into the furnace. Of course, instead of the screws described, any other suitable conveying or feeding means can be provided so as to bring about an intimate mixture. 75

The air entering the member 24 may be by means of a draft caused by the combustion or by suitable mechanical means; the important feature, however, being that this air-current should not be of great velocity, the object of the invention being to 80 provide means by which fuel is fed into the mixing chamber in a finely-divided condition, by reason of which finely-divided condition the fuel can be conveyed by a current of 85 air of low velocity into the part of the furnace in which combustion takes place. The arrangement of the air-current in the feeding orifices will cause the feeding orifices to remain cool and prevent them from being 90 choked by the direct action of the heat. The box 27 may be widened toward the place where the combustion takes place, so that the air-current, after being mixed with the pulverized fuel, may be lowered in velocity and 95 prevent a flame of the character, of a blowpipe. 100

I have shown one form of apparatus suitable for carrying out the invention. It is obvious, however, that the process may be 105 carried out in apparatus of other forms, without departing from the spirit of the invention as defined in the appended claim.

I claim:

In the art of burning pulverized fuel, that 110

step in the art which consists in feeding fuel in a plurality of separated and individualized streams adjacent each other, successively to an air current, while the latter 5 gradually expands and the velocity thereof is being gradually reduced, thereby mixing throughout substantially sufficient air for complete combustion before entering the furnace, said fuel being maintained below 10 the ignition point during the mixing, and feeding the mingled current of air and fuel

to the furnace at a diminished velocity, whereby the fuel burns with a short broad flame.

In testimony that I claim the foregoing 15 as my invention, I have signed my name in presence of two subscribing witnesses.

VIRGINIUS Z. CARACRISTI.
